UNITED STATES PATENT OFFICE.

MENDEL OSNOS, OF BERLIN, GERMANY, ASSIGNOR TO GESELLSCHAFT FÜR DRÄTLOSE TELEGRAPHIE M. B. H., OF BERLIN, GERMANY, A CORPORATION OF GERMANY.

STATIC FREQUENCY CHANGER.

Application filed October 20, 1925, Serial No. 63,615, and in Germany September 16, 1924.

My invention relates to arrangements for changing electrical energy of one frequency into electrical energy of another frequency, and, more particularly, to such an arrangement in which there are no moving parts. The invention relates not only to frequency changing but also to modulation and more particularly to a combined apparatus therefor.

10 The invention, in general, utilizes a Wheatstone's bridge magnetic circuit with a suitable primary circuit of the input frequency and a secondary circuit of the output or useful frequency associated therewith. 15 One arrangement according to the invention is somewhat similar to that in German patent application No. 29,298 filed in Germany September 12, 1924, the corresponding United States application being filed under 20 Serial No. 63,618 on October 20, 1925, wherein a scheme for modulation was disclosed, making use of a novel conductor formed of a core of conducting material provided with an outer layer or coating of magnetic material.

25 The usual type of frequency changer introduces high losses, and furthermore, it is extremely difficult to dissipate the heat caused by its losses. This problem becomes especially acute at the high frequencies employed in short wave work. It is an object of my invention to overcome the difficulty of heat dissipation and to reduce the losses accompanying the change of frequency.

30 35 It is a further object of my invention to combine controlling or modulating means with a frequency changing means in a simple manner requiring practically no additional apparatus.

40 45 Another object of the invention is to provide a frequency changer which will be cheap to manufacture and yet simple and efficient in operation. Another object of this invention is to provide a frequency changer which will be adjustable and thereby eliminate the necessity of separate adjusting inductances.

50 Other objects will be apparent from the following description and appended claims when considered with the accompanying drawings in which,

Fig. 1 is a diagrammatic arrangement of the conductors as in the former application,

Fig. 2 represents an arrangement of an old type frequency changer, 55

Fig. 3 represents an arrangement according to the invention,

Figs. 4, 5, 7, and 8 represent modifications, and

Fig. 6 is a cross section, greatly exaggerated, 60 of the novel conductor used according to the invention.

Figure 9 is a modification showing the application of telephony modulation to the high frequency energy, 65

In the former application a controlling arrangement for the high frequency conductor has been described. Referring to Fig. 1, this arrangement in a fundamental form consists of a complex conductor made up 70 of a plurality of conductors forming branches a_1 , a'_1 , a_2 , and a'_2 arranged as shown. The branches are connected in a form somewhat similar to a Wheatstone's bridge, the branches a_1 and a'_1 being close 75 to and parallel to branches a_2 and a'_2 respectively. Each conductor or branch is formed of a core of conducting material 10 such as copper (Fig. 6) covered by a layer 80 of magnetic material 11 such as iron or some alloy thereof. The layer of magnetic material is preferably very thin to give the necessary magnetization and heat radiating surface per unit of volume. The conductor for the current is traversed not only by the 85 high frequency currents, but also by the controlling or modulating currents. Relative to the high frequency current fed in at the axis K_1 , K_2 the arrangement is bifilar, that is, the high frequency current traverses the bifilar 90 branches a_1 and a_2 in opposite directions and likewise the bifilar branches a'_1 and a'_2 . For this current, the magnetic flux (stray flux) which does not pass through the iron sheath or covering, and jointly therewith also the 95 stray inductance, are almost entirely eliminated. However, for the current in the 1_1 , 1_2 axis, the arrangement as here illustrated is not bifilar, and the stray inductance is undiminished. If the same is to be eliminated, 100 the branches a'_1 and a'_2 must be turned about axis K_1 , K_2 by an angle of about 180 degrees as shown dotted in Figure 1, a_1 becoming a_2 , b_1 becoming b_2 , and 1_1 becoming $1_1'$.

If one further examines the axis 1_1 , 1_2 in 105 which the controlling or modulating current

- is supplied, it will be noted that in this axis owing to the different superposition of the magnetic fluxes in different branches, high frequency potentials of a whole multiple frequency are produced by the high frequency currents of the other axis. Now, according to the present invention, this circumstance can be utilized for the derivation of useful energy of a whole multiple frequency, for at the axis $1_1, 1_2$ of the modulating currents, the secondary currents of a whole multiple value may be taken off, if at the other axis K_1, K_2 primary currents of basic high frequency are fed in.
- Since it is furthermore possible to eliminate at will, or, if desired, to increase both the primary as well as the secondary leakage (stray) inductance independently of one another by suitable formation of the complex conductor, as by elongation or sufficient deflection or bending away of the branches in different axes, this constitutes an excellent tuning means for the system whereby separate tuning variometers may be rendered wholly or partly dispensable.

Considering, for instance, a high frequency installation of the well known type as depicted in Fig. 2 comprising a high frequency source g , parallel capacitance C_p , a series capacitance C_s , a tuning variometer L_1 , and a frequency changer T of any of the types heretofore well known, it will be seen that, in order to preclude useful or output currents of multiple frequency f_2 of the secondary circuit II from the primary circuit I, the variometer L_1 must be chosen sufficiently large to choke out the frequency f_2 ; hence, it constitutes a considerable source of losses.

The frequency changer T may be a static frequency changer comprising a core of magnetic material such as iron with a primary and secondary circuit connected thereto, said circuits being connected either to the same winding, such as shown in the drawing or to separate windings, as is well known in the art.

Now, this varicometer L_1 can be dispensed with if, in lieu of the customary current transformer the arrangement of a current conductor disclosed in the application above referred to is used. A connection of this sort is depicted diagrammatically in Fig. 3.

No frequency changer in the former sense of the term is here used. Instead, part of the leads are constructed in the manner of the conductor disclosed in the former application. The primary fundamental or basic current is here supplied at the axis $1_1, 1_2$, and it flows in the branches a_1, a_1' as well as in the branches a_2, a_2' in the same direction. Hence, in this axis, the primary stray inductance remains unchanged, and if of sufficient value, it may be made use of to take the place of the self inductance of the

variometer L_1 of Fig. 2, which may then be entirely dispensed with, or which, if condenser C_1 , instead of being continuously variable is only variable in steps, may be replaced by a small regulating variometer L (Fig. 3) which only serves for overlapping or bridging the increments or stepwise changes in condenser C_1 . However, even in this case the small variometer could be dispensed with if the self inductance of the conductor serving as the current transformer is made variable for the axis $1_1, 1_2$. As a simple example, consider the bending of the axis $1_1, 1_2$, about the axis k_1, k_2 , as was previously suggested, and which is indicated by the dotted lines in Figure 3.

The current required, for instance, for the auxiliary magnetization (most suitably direct current magnetization) is fed, for instance, from a battery b by way of a protective inductance d to the axis k_1, k_2 and from this same axis there is derived or taken off the secondary high frequency current of whole multiple frequency. The conductor serving as the frequency changer may be bifilar with reference to the direct current and the secondary current, and therefore is free from secondary stray inductance.

If it is desired to eliminate the inductance L_1 of Figure 2, and if the primary stray inductance in the axis $1_1, 1_2$ is not high enough, it may be increased in several ways. For example, the conductor in question may be lengthened. But a better scheme would be to wind it into a sufficiently great number of round or angular turns or spirals in order to concentrate the stray flux just as an ordinary coil concentrates the total flux. This has been illustrated in Figure 8. If desired, the resulting bifilar coil may be made in two parts relatively positioned in a variable manner, as for example, in a variometer, whereby the stray inductance for the axis $1_1, 1_2$ is raised to the desired large amount and at the same time rendered regulable, without the secondary stray inductance being affected thereby. The latter, as heretofore, remains very low, in view of the fact that the conductors when rolled up remain bifilar with relation to the axis k_1, k_2 . For telephony, a direct current may be varied by a microphone instead of a key. This, as well as a diagram for a variometer connection for the frequency changer, has been indicated in Figure 9.

For the purpose of keying and telephony work, it is most suitable to vary the direct current furnished from the battery b ; although of course, the work of telegraphing or telephoning could also be accomplished in some other of the various well known manners. For telegraphy, as an illustration, the direct current may be varied by key 20 as shown in Figure 3.

The terminals k_1, k_2 are most conveniently

disposed in a symmetrical manner with reference to the terminals 1_1 1_2 , but this is not absolutely necessary.

In case it is desired to diminish the primary stray inductance and to increase the secondary stray inductance, or if any relationship at all is to be established between them, this is made possible in any given case by the convenient shaping or bending of the branches making up the frequency changer. By bending or shaping the branches of the frequency changer making up a Wheatstone bridge the area enclosed by the sides of the Wheatstone bridge is altered, thereby varying the stray inductance effects and giving adjustability to the frequency changer. Positioning of two adjacent branches in a single plane has been indicated in Figure 4, where a_2^1 is a possible altered position of a_2 . Such adjustable positioning may be applied to the complete bridge of Figure 3, the adjustment in each case depending upon the particular conditions to be met.

Furthermore, it is not absolutely necessary to build the frequency changer of four like branches. Figs. 4 and 5 illustrate a construction comprising but two iron coated branches a_1 and a_2 of like nature. In both cases the primary current is supplied at the axis 1_1 and 1_2 , while the secondary current is taken off at the axis k_1 and k_2 . In the case of Fig. 4 the battery serves at the same time as a voltage divider, and therefore carries also the primary currents. In the case of Fig. 5 the battery b is again safeguarded against the primary currents by choke coil d , while the voltage divider used consists of a bridge made up of an inductance e . The lower branches of the bridge may be capacitive as indicated in Figure 7, wherein the voltage divider consists of the capacitance c_1 , c_2 .

In the presence of extra high frequencies, for raising the power and the efficiency it is a very advantageous plan to maintain the iron of the conductor constituting the frequency changer in a state of incandescence, especially in the vicinity of the critical temperature point of the iron.

Having described my invention, I am entitled to all modifications thereof that come fairly within its spirit and scope as set forth in the following claims:

1. A frequency changer arrangement including a branch circuit consisting of a core of conducting material surrounded by a layer of magnetic material whereby much of the flux caused by current in the branch cuts said branch only, a primary circuit containing a source of a supply frequency connected to said branch, a secondary circuit of desired frequency connected to said branch and a source of auxiliary magnetization connected to said branch.

2. A frequency changer arrangement in-

cluding, a plurality of branches in the form of a Wheatstone's bridge, two of said branches being relatively adjustable and each comprising a core of conducting material surrounded by a layer of magnetic material whereby much of the flux caused by current in the branch cuts said branch only, a primary circuit containing a source of a supply frequency connected across diagonally opposite corners of said bridge, a secondary circuit of the desired frequency connected across the other corners of said bridge, and a source of auxiliary magnetization connected across one pair of diagonally opposite corners. 70 75 80

3. A frequency changer arrangement including, a plurality of branches in the form of a Wheatstone's bridge, two of said branches being relatively adjustable and of compound material, each comprising a core of conducting material surrounded by a layer of magnetic material whereby much of the flux caused by current in the branch cuts said branch only, a primary circuit containing a source of a supply frequency connected across diagonally opposite corners of said bridge, a secondary circuit connected across the other corners of said bridge, and a source of auxiliary magnetization connected across one pair of diagonally opposite corners, said branches of compound material being adapted to be heated to work the magnetic material at its critical temperature. 90 95

4. A frequency changer arrangement including, a plurality of branches in the form of a Wheatstone's bridge, each branch comprising a core of conducting material surrounded by a layer of magnetic material whereby much of the flux caused by current in the branch cuts said branch only, a primary circuit containing a source of a supply frequency connected across diagonally opposite corners of said bridge, a secondary work circuit for the desired frequency connected across the other corners of said bridge, and a source of auxiliary magnetization connected across one pair of diagonally opposite corners, said branches being adapted to be adjusted relative to each other to control the stray inductances of said circuits. 100 105 110

5. A frequency changer arrangement including, branches in the form of a Wheatstone's bridge, each of a plurality of said branches comprising a core of conducting material surrounded by a layer of magnetic material whereby much of the flux caused by current in the branch cuts said branch only, a primary circuit containing a source of a supply frequency connected across diagonally opposite corners of said bridge, a secondary circuit for the desired changed frequency connected across the other corners of said bridge, and a source of auxiliary magnetization connected across one pair of diag- 120 125 130

onally opposite corners, said branches being adjustable to control their stray inductance.

6. A frequency changer arrangement including, a plurality of branches in the form of a Wheatstone's bridge, each branch comprising a core of conducting material surrounded by a layer of magnetic material whereby much of the flux caused by current in the branch cuts said branch only, a primary circuit containing a source of a supply frequency connected across diagonally opposite corners of said bridge, a secondary circuit for the desired frequency connected across the other corners of said bridge, and 10 a source of auxiliary magnetization connected across said other corners, said branches being adapted to be adjusted relative to each other to adjust the stray inductances of said circuits.
- 20 7. A frequency changer arrangement including, branches in the form of a Wheatstone's bridge, each of a plurality of branches being made of compound material comprising a core of conducting material surrounded by a layer of magnetic material whereby much of the flux caused by current in the branch cuts said branch only, a primary circuit containing a source of a supply frequency connected across diagonally opposite 25 site corners of said bridge, a secondary circuit for the desired frequency connected across the other corners of said bridge, and a source of auxiliary magnetization connected across one pair of diagonally opposite corners, the compound branches being arranged in bifilar relation.

8. A frequency changer including a plurality of branches in the form of a Wheatstone's bridge, saturable impedances in at 40 least some of said branches, a primary circuit containing a source of a supply frequency connected across diagonally opposite corners of said bridge, and a secondary circuit for the desired frequency connected across the other corners of said bridge, said branches being positioned in bifilar relation.

9. A frequency changer including a plurality of branches in the form of a Wheatstone's bridge, saturable impedances in at 50 least some of said branches, a primary circuit containing a source of a supply frequency connected across diagonally opposite corners of said bridge, a secondary circuit for the desired frequency connected across the other corners of said bridge, and a source of magnetizing energy arranged for magnetization of the saturable impedances, said branches being positioned in bifilar relation with respect to the path of the secondary energy.

10. A frequency changer including a plurality of branches in the form of a Wheatstone's bridge, saturable impedances in at least some of said branches, a primary cir-

cuit containing a source of a supply frequency connected across diagonally opposite corners of said bridge, a secondary circuit for the desired frequency connected across the other corners of said bridge, and a source of magnetizing energy arranged for magnetization of the saturable impedances, said branches being positioned in bifilar relation with respect to the path of the magnetizing energy.

11. In combination, a network of compound conductors connected like the branches of a Wheatstone's bridge, and a source of current connected across the bridge, each compound conductor being composed of a core of conducting material surrounded by a layer of magnetic material whereby much of the flux caused by current in the conductor cuts said conductor only, the branches being so relatively positioned that the remaining or stray flux caused by current from said source is neutralized.

12. In combination, a network of compound conductors connected like the branches of a Wheatstone's bridge, and a source of current connected across the bridge, each compound conductor being composed of a core of conducting material surrounded by a layer of magnetic material whereby much of the flux caused by current in the conductor cuts said conductor only, the branches being so relatively positioned that the remaining or stray flux caused by current flowing thru the bridge from one corner to a diagonally opposite corner is neutralized.

13. A frequency changer including a single bifilar wound inductance comprising a plurality of branches of a Wheatstone's bridge, and circuits associated therewith, said inductance being wound of a compound conductor composed of a core of conducting material surrounded by a layer of magnetic material.

14. A frequency changer including a single bifilar wound inductance comprising four branches of a Wheatstone's bridge, and input, output, and saturating circuits associated therewith, said inductance being wound of a compound conductor composed of a core of conducting material surrounded by a layer of magnetic material.

15. A frequency changer comprising a Wheatstone's bridge including two wound inductances adapted for variable relative positioning, each of which comprises two of the branches of the said Wheatstone's bridge, and input, output, and saturating circuits associated therewith, said inductance being wound of a compound conductor composed of a core of conducting material surrounded by a layer of magnetic material.

16. A frequency changer having as its harmonics generator a Wheatstone's bridge the

four branches of which are impedances, a plurality of which include a compound conductor comprising a core of conducting material surrounded by a layer of magnetic material.

17. A frequency changer having as its harmonics generator a Wheatstone's bridge,

the four branches of which are impedances, a plurality of which include a compound conductor which is movable and which comprises a core of conducting material surrounded by a layer of magnetic material.

MENDEL OSNOS.
